(57) **CLAIM**

The ornamental design for a kneeling pad, as shown and described.

DESCRIPTION

FIG. 1 is a perspective view of a single handle kneeling pad.

FIG. 2 is a right side elevational view of the invention shown in FIG. 1.

FIG. 3 is a top plan view of the invention shown in FIG. 1.

FIG. 4 is a bottom plan view of the invention shown in FIG. 1.

FIG. 5 is a left side elevational view of the invention shown in FIG. 1.

FIG. 6 is a rear plan view of the invention shown in FIG. 1.

FIG. 7 is a front plan view of the invention shown in FIG. 1.

FIG. 8 is a perspective view of a two handle embodiment of the kneeling pad.

FIG. 9 is a right side elevational view of the invention shown in FIG. 8.

FIG. 10 is a top plan view of the invention shown in FIG. 8.

FIG. 11 is a left side elevational view of the invention shown in FIG. 8.

FIG. 12 is a bottom plan view of the invention shown in FIG. 8.

FIG. 13 is a rear plan view of the invention shown in FIG. 8; and,

FIG. 14 is a rear plan view of the invention shown in FIG. 8.
